UNITED STATES PATENT OFFICE.

HENRY A. BERENDSEN, OF BANGOR, PENNSYLVANIA.

REFOOTING STOCKINGS.

1,424,708.

Specification of Letters Patent. Patented Aug. 1, 1922.

Application filed December 23, 1920. Serial No. 432,734.

To all whom it may concern:

Be it known that I, HENRY A. BERENDSEN, a citizen of the United States, and a resident of Bangor, in the county of Northampton and State of Pennsylvania, have invented new and useful Improvements in Refooting Stockings, of which the following is a full, clear, and exact description.

The invention relates to hosiery of the more expensive type and made of woven silk cloth (tricot or Milanese) or embroidery material.

The object of the invention is to provide certain new and useful improvements in refooting stockings having torn soles, toes or heels, to render the stocking practically as good as new.

Another object is to permit a stocking to be refooted a number of times at a comparatively low cost thus saving considerable expense in the use of hosiery.

With these and other objects in view, the invention consists of certain novel features of construction as hereinafter shown and described, and then specifically pointed out in the claim.

A practical embodiment of the invention is represented in the accompanying drawings forming a part of this specification, in which similar characters of reference indicate corresponding parts in all the views.

Figure 1 is a side elevation of a torn stocking to be refooted;

Figure 2 is a similar view of the same after being refooted;

Figure 3 is a perspective view of the leg and integral foot top as it appears after cutting the damaged heel, sole and toes of the stocking shown in Figure 1;

Figure 4 is a perspective view of the new reinforced upper toe portion;

Figure 5 is a similar view of the new reinforced heel; and

Figure 6 is a similar view of the sole with the integral reinforced bottom toe portion.

Stockings of woven silk or silk embroidery material are liable to tear mainly at the heels, toes and sole, and very small holes can be temporarily closed by darning. A pair of stockings eventually becomes unfit for wear and has to be discarded and replaced by a new pair at a considerable expense to the wearer. In order to reduce this expense to a minimum and to render the stocking of a pair as good as new the stockings are refooted with the same mate-

rial at approximately one-quarter of the cost of a new pair, and this refooting can be repeated, at least, four or five times before the leg and top of the foot of a stocking is completely worn out. On the presumption that a pair of woven silk stockings at an original wholesale cost of say \$4.00 has been refooted five times at an expense \$1.00 each time, the total cost is only \$9.00 against six new pairs at a cost of \$24.00.

In order to produce the desired result, the following arrangement is made: The stocking shown in Figure 1 is made of woven silk (tricot or Milanese) and comprises a single ply leg 10, a single ply foot top 11, a reinforced or doubled heel 12, a single ply sole 13 and a toe made of top and bottom reinforced or doubled portions 14 and 15. The heel 12 and the toe portions 14 and 15 are reinforced in the usual manner, that is, are made of double or two ply material. Originally in making this stocking the leg 10, the foot top 11, the upper toe portion 15 and the heel 12 are made of a single piece of woven material, and the heel 12 and the upper toe portion 15 are reinforced at the inside by corresponding pieces thus making the same double. The sole 13 including the lower toe portion 14 is made of a single piece of material, and the said lower toe portion is reinforced at the inside by a corresponding piece. The two members are seamed together, that is, the side edges of the sole 13 are seamed to the side edges of the foot top 11, the rear edge of the sole 13 is seamed to the front edge of the heel 12, and the top edge of the lower toe portion 14 is seamed to the bottom edge of the upper toe portion 15, as will be readily understood by reference to Figure 1. The heel 12, the sole 13 and the toe portions 14, 15 on account of being torn, as indicated in Figure 1, are cut off from the leg 10 and foot top 11 and thrown away, and corresponding new pieces of similar size, shape and material are provided, namely, a reinforced heel 12^a, a single ply sole 13^a terminating in an integral bottom toe portion 14^a reinforced at the inside, and a reinforced or double top toe portion 15^a. The original leg 10 and the foot top 11 are turned inside out, and then the several new pieces are joined to the original leg 10 and foot top 11 while likewise turned inside out position and in the following sequence: The heel 12^a is seamed with its upper edge onto

the lower end of the leg 10, the top toe portion 15^a is seamed onto the front end of the foot top 11, the sole 13^a with the bottom toe portion 14^a is next seamed to the several parts, that is, its side edges are seamed to the side edges of the foot top 11, the rear edge of the sole 13^a is seamed to the front edge of the heel 12^a and the bottom toe portion 14^a is seamed to the top toe portion 15^a. When this has been done the stocking is reversed and is then ready to be returned to the owner.

It will be noticed that the lower edge of the leg 10 and the top edge of the reinforced heel 12^a are inclined upwardly and rearwardly, terminating in a point at the back of the stocking, thus giving a graceful appearance to the stocking. The upper heel point is located higher or lower on the

back of the stocking (see dotted lines in Figure 2) according to the tear or tears in the heel or in the lower portion of the leg of the stocking to be refooted, that is, in each case this point is located above the highest tear at the back of the heel or that of the original leg 10.

It is understood that in practice a torn pair of stockings is returned to the manufacturer for refooting and then the refooted pair of stockings is returned to the owner on payment of the cost, as above stated.

It is also understood that the refooting of stockings as described is more especially

designed for stockings made of woven fabrics such as silk tricot or Milanese woven silk goods in contradistinction to knit stockings to allow of readily cutting out the defective parts without danger of unraveling. Likewise the parts used for refooting are cut from the goods in the piece and securely sewed in place without danger of unraveling. Although the invention does not contemplate the refooting of knit stockings it includes refooting of stocking made of embroidery material which similar to the woven material permits cutting without danger of unraveling and which allows of securely sewing the parts together.

Having thus described my invention, I claim as new and desire to secure by Letters Patent:

As an article of manufacture, a refooted stocking comprising a woven single ply fabric leg merging into a single ply foot top section, a re-inforced woven fabric toe top section seamed to the front end of said foot top section, a re-inforced woven heel section seamed to the edges of said leg, and a single ply woven sole formed with a woven re-inforced toe section, said sole with its re-inforced toe section being seamed to the edges of said toe top section and to the edges of said foot top section, one end of said sole being also seamed to said reinforced heel section.

HENRY A. BERENDSEN.
